ASH RECEPTACLE

William G. Vogel, Grand Rapids, Mich., assignor
to Michigan Bumper Corporation, Grand Rap-
ids, Mich., a corporation of Michigan

Application December 23, 1935, Serial No. 55,795

17 Claims. (Cl. 206—19.5)

- This invention relates to an ash receptacle and more particularly to ash receptacles of the type adapted to swingably move into and out of an opening in an automobile panel.
- 5 It is the object of this invention to provide a receptacle which may be moved to open or closed position with a minimum of effort, which will automatically assume closed position as it approaches closed position, and which will at the same time positively prevent rattling in open or closed position; the above being possible by a roller bearing resiliently carried by the receptacle and movable relative to a guide.
- 10

Another feature of the invention has to do with a combined reinforcing and guide member which cooperates with the roller member and which at the same time provides a rigid compact assembly for withstanding severe jolts, vibration, and possible abusive use of the ash receptacle. Other novel features have to do with details of structure and arrangement as is more clearly set forth in the specification and claims.

In the drawings:

Fig. 1 is a side elevation of one embodiment of the ash receptacle, shown in normal closed position.

Fig. 2 is a front elevation of the structure as shown in Fig. 1.

Fig. 3 is a sectional view taken on line 3—3 of Fig. 1, illustrating the resiliently carried roller as positioned relative to the guide when the receptacle is in closed position.

Fig. 4 is a view similar to Fig. 1, showing the receptacle moved to its outer ash receiving position.

Fig. 5 is a side elevation of the modified form of the receptacle wherein the tray is removable, the receptacle and tray being shown in open position in dotted lines.

Fig. 6 is a fragmentary rear view taken at 6—6 of Fig. 5, showing particularly the relation of the reinforcing guide member relative to the receptacle.

Fig. 7 is a view similar to Fig. 6, and illustrating a further modified form in that the removable tray unit of Fig. 6 is shown in combination with a guide member of the general type shown in Fig. 1.

In the various figures, the wall or panel unit of an automobile or the like is generally designated 2, with an inturned portion 3, carrying a pair of spaced lugs or fulcrum members 4. The receptacle is generally designated 5, and is provided with a downwardly extending arm 6 carrying a pivot pin 7. This construction permits the

receptacle to be inserted through the opening 8 of the panel 2, and permits oscillation of the receptacle into open or closed position; the structure above explained being of more or less standard design.

5 The receptacle 5 is provided with a front ornamental panel 9, this panel being adapted to contact with the instrument panel or other wall member 2, in the closed position of the receptacle, a rubber bumper or other means usually being utilized to make the closing substantially noiseless. A guide member 10 is secured to and extends rearwardly from the panel 2; the guide member being arcuate in shape and provided with an embossed bead or runway 11. This bead 15 terminates short of the rear end of the guide member 10 as at a point 12 and the other end of the bead terminates short of the front end of the guideway as at a point 13, a stop 14 being stamped out just ahead of the end 13 of the bead 11.

A roller member 15 adapted to cooperate with the guide 10 and the bead 11 is resiliently carried by means of a spring 16, secured to the rear wall of the receptacle 5 and extending up over the receptacle and terminating in a lever member 17. The roller 15 is held in position by means of turned up ears 18 formed at the side of the spring member 16, as best shown in Figure 3.

In assembly and use, the arm 6 may be inserted through the opening 8 and moved downwardly into contact with the fulcrum member 4. Moving the receptacle inwardly, the roller 15 will contact with the stop 14 and be pressed downwardly or may be pressed downwardly by 30 actuating the lever 17. The roller bearing 15 contacting with the bead 11 will obviously result in extremely easy movement of the receptacle back and forth about the pivot 7, and because of this ease of movement, the spring 16 may be 35 made much stronger than that type of receptacle and guide where the contact is directly between the spring and the guide. As the roller bearing 15 approaches the end 12 of the bead 11, and starts to move around the cam surface formed by 40 the end of the bead, it will be seen that the receptacle will be automatically moved "home" because of the cooperating force and effect between the cam surface 12, the roller bearing 15 and the spring 16. The same action takes place when the 45 receptacle is opened and the roller 15 moves past the cam surface at the point 13 and against the stop 14, as best shown in Figure 4. Thus not only will the receptacle be automatically moved to position at each end of the opening and closing 50

stroke but while the receptacle is completely opened or completely closed, as determined by the cam surfaces 13 and 12, or as the roller is moving along the bead 11, the pivot 7 of the receptacle will be securely forced against the fulcrum lugs 4 due to the strong action of the spring 16. The direct result of this structure and movement is that the receptacle may be easily moved in and out, firmly held in either open or closed position, and at the same time positively prevented from rattling in any position.

It will be seen that when the receptacle is moved to the position shown in Figure 4, if desired, the entire receptacle may be removed by placing down the lever 17 sufficiently to allow the roller 15 to pass the stop 14.

In the modification shown in Figures 5 to 7, the receptacle is made up of a frame 5a and a removable container 5b, the receptacle 5a taking the same general form as the one piece receptacle 5 shown in Figure 1. The back of the removable container 5b preferably terminates as at a point 20, and the frame 5a is provided with a cross member 21 to which is secured a spring 22. This spring 22 is similar to the spring member 16 and has a downward extension 23, which is adapted to contact with an offset part of the removable container 5b as at a point 24.

The upper end of the spring 22 carries a roller 25, in the same manner as illustrated in connection with Figures 1 to 4, and this roller cooperates with the bead 26 of a guide member 27, which as far as the upper part thereof, is similar to the guide member 10, as shown in Figure 1. The guide member 27 in addition to being secured to the panel 2 above the ash receptacle, also continues completely around the receptacle, along the back thereof as at 28 and is then secured to the inturned portion 3 as at 29. This arrangement of the guide provides a very sturdy guide member which will not break off nor be distorted as is often the case with top guide members of the type shown in Figure 1.

An important feature of the spring shown in Figures 5, 6 and 7 is that it performs three essential functions, first, due to the shape of the neck portion, provides a resilient mounting for the roller 25, second, it serves to force the pivot 7 home on the fulcrum at all times and thus prevents the receptacle from rattling and third, the lower end of the spring, contacting with the removable receptacle 5b, resiliently holds the same in position.

The form of the receptacle shown in Figure 5 carries its own cover, in that a cover member 30 is pivotally connected as at 31 to the top of the removable container 5b; a spring 32 being arranged around the pivot 31 to normally tend to move the cover 30 to open position, as shown in dotted lines in Figure 5. It will thus be seen that movement of the receptacle inwardly from the dotted line position shown in Figure 5, will cause the cover 30 to be forced downwardly against the action of the spring 32, and vice versa upon opening of the receptacle, the cover 30 will be automatically raised.

In Figure 7, I have shown an arrangement similar to that shown in Figure 5 except that instead of a reinforcing guide member 27 extending all the way around the receptacle, I have used a guide member 35 which is in the form of a cover for the top of the receptacle in addition to being a guide member, this combined cover and guide member being provided

with a bead 36 and attached to the panel 2 in the same manner as the guide member 27.

What I claim is:

1. An ash receptacle unit of the class described, comprising a panel having an opening, a swinging receptacle, the lower end of which is pivotally mounted, an arcuate guide member extending rearwardly from said panel, and a roller bearing resiliently mounted on the upper rear part of said receptacle and contacting with said guide member to permit easy movement of said receptacle and to hold said receptacle in said pivotal mounting under pressure at all times to prevent rattling.

2. An ash receptacle unit of the class described, comprising a panel having an opening, a swinging receptacle, the lower end of which is pivotally mounted, an arcuate guide member extending rearwardly from said panel, and a roller bearing resiliently mounted on the upper rear part of said receptacle and contacting with said guide member to permit easy movement of said receptacle and to hold said receptacle in contact with said mounting at all times to prevent rattling.

3. An ash receptacle unit of the type adapted to fit into a panel opening, comprising a pivotal mounting for the lower end of said unit, an arcuate guide member extending rearwardly from said panel and to a point adjacent the upper rear part of said unit, an embossed bead positioned on the under side of said guide member and terminating short of the rear end of said guide member, and a roller bearing resiliently mounted adjacent the upper edge of said receptacle and adapted to contact with said bead to permit easy movement of said receptacle about said pivot, said resilient mounting permitting bodily movement of said roller to adjust itself to said bead and being of such strength as to permit easy swinging movement of said receptacle because of the anti-friction contact between the roller and the bead and at the same time maintain sufficient pressure between said receptacle and the pivotal mounting to prevent rattling.

4. An ash receptacle unit of the type adapted to fit into a panel opening, comprising a pivotal mounting for the lower end of said unit, an arcuate guide member extending rearwardly from said panel and to a point adjacent the upper rear part of said unit, an embossed bead positioned on the under side of said guide member and a roller bearing resiliently mounted adjacent the upper edge of said receptacle and adapted to contact with said bead to permit easy movement of said receptacle about said pivot, said resilient mounting permitting bodily movement of said roller to adjust itself to said bead and being of such strength as to permit easy swinging movement of said receptacle because of the anti-friction contact between the roller and the bead and at the same time maintain sufficient pressure between said receptacle and the pivotal mounting to prevent rattling.

5. An ash receptacle unit of the type adapted to fit into a panel opening, comprising a pivotal mounting for the lower end of said unit, an arcuate guide member extending rearwardly from said panel and to a point adjacent the upper rear part of said unit, and a roller bearing resiliently mounted adjacent the upper edge of said receptacle and adapted to contact with said guide to permit easy movement of said receptacle about said pivot, said resilient mounting permitting

5 bodily movement of said roller to adjust itself to said bead and being of such strength as to permit easy swinging movement of said receptacle because of the anti-friction contact between the 5 roller and the guide and at the same time maintain sufficient pressure between said receptacle and the pivotal mounting to prevent rattling.

6. An ash receptacle unit of the class described, comprising a panel having an opening, a pivotal 10 mounting for the lower end of said unit, an arcuate guide member adjacent the upper part of said unit, an embossed bead positioned on the under side of said guide member and terminating short of the rear end of said guide member, and 15 a roller bearing resiliently mounted adjacent the upper edge of said receptacle and adapted to contact with said bead to permit easy movement of said receptacle about said pivot, said resilient mounting being of such strength as to permit easy swinging movement of said receptacle because of the anti-friction contact between the 20 roller and the bead and at the same time maintain sufficient pressure between said receptacle and the pivotal mounting to prevent rattling, said 25 roller bearing being so positioned relative to the end of said bead that said roller bearing will pass over the end of said bead as the front of the receptacle contacts with the panel whereby to resiliently hold the panel in closed position.

30 7. An ash receptacle unit of the class described, comprising a panel having an opening, a pivotal mounting for the lower end of said unit, an arcuate guide member adjacent the upper part of said unit, an embossed bead positioned on the under side of said guide member and terminating short of the rear end of said guide member, an 35 anti-friction member resiliently mounted adjacent the upper edge of said receptacle and adapted to contact with said bead to permit easy movement of said receptacle about said pivot, said resilient mounting being of such strength as to permit easy swinging movement of said receptacle because of the anti-friction contact between the member and the bead and at the same time 40 maintain sufficient pressure between said receptacle and the pivotal mounting to prevent rattling, said member being so positioned relative to the end of said bead that said member will pass over the end of said bead as the front of the receptacle contacts with the panel whereby to resiliently hold the panel in closed position.

45 8. An ash receptacle of the class described comprising a panel having an opening, a pivotal mounting for the lower end of said unit, an arcuate guide member adjacent the upper part of said unit, an embossed bead positioned on the under side of said guide member and terminating short of the rear end of said guide member, and a bearing resiliently mounted adjacent the upper edge of said receptacle and adapted to contact with said bead to permit easy movement of said receptacle about said pivot, said resilient mounting being of such strength as to permit easy swinging movement of said receptacle because of the anti-friction contact between the bearing and the bead and at the same time maintain sufficient pressure between said receptacle and the pivotal mounting to prevent rattling, said bearing being so positioned relative to the end of said bead that said bearing will pass over the end of said bead as the front of the receptacle contacts with the panel whereby to resiliently hold the panel in closed position, the other end of said bead terminating short of the front end of said 50 guide member whereby the bearing will pass over

the other end of said bead to resiliently hold the receptacle in open position.

9. An ash receptacle unit of the class described, comprising a panel having an opening, a pivotal mounting for the lower end of said unit, 5 an arcuate guide member adjacent the upper part of said unit, an embossed bead positioned on the under side of said guide member and terminating short of the rear end of said guide member, and a roller bearing resiliently mounted 10 adjacent the upper edge of said receptacle and adapted to contact with said bead to permit easy movement of said receptacle about said pivot, said resilient mounting being of such strength as to permit easy swinging movement of said receptacle 15 because of the anti-friction contact between the roller and the bead and at the same time maintain sufficient pressure between said receptacle and the pivotal mounting to prevent rattling, said roller bearing being so positioned relative to the 20 end of said bead that said roller bearing will pass over the end of said bead as the front of the receptacle contacts with the panel whereby to resiliently hold the panel in closed position, the other end of said bead terminating short of the front 25 end of said guide member whereby the roller will pass over the other end of said bead to resiliently hold the receptacle in open position, and a stop member positioned adjacent the other end of said 30 bead to firmly hold the receptacle against rattling 35 while resiliently held in open position.

10. A receptacle unit of the class described, comprising a panel having an opening, a receptacle pivotally mounted at its lower end adjacent the rear side of said panel, a guide member extending rearwardly from said panel and adjacent the upper end of said receptacle and continuing on around said receptacle and connected to said panel adjacent the lower end of said receptacle whereby to form a reinforcing and guide unit, 40 and anti-friction means resiliently carried by said receptacle and contacting with said guide member to permit easy swinging movement of the receptacle through said opening.

11. A receptacle unit of the class described, 45 comprising a panel having an opening, a receptacle pivotally mounted at its lower end adjacent the rear side of said panel, a guide member extending rearwardly from said panel and adjacent the upper end of said receptacle and continuing on around a portion of said receptacle and connected to said panel whereby to form a reinforcing 50 and guide unit, and anti-friction means resiliently carried by said receptacle and contacting with said guide member to permit easy swinging movement of the receptacle through said opening.

12. A receptacle unit of the class described, comprising a panel having an opening, a receptacle pivotally mounted at its lower end adjacent the rear side of said panel, a guide member extending rearwardly from said panel and adjacent the upper end of said receptacle and continuing on around said receptacle and connected to said panel adjacent the lower end of said receptacle whereby to form a reinforcing and guide unit, and anti-friction means resiliently carried by said receptacle, and contacting with said guide member to permit easy swinging movement of the receptacle through said opening, said resilient mounting being so arranged as to permit limited 60 bodily movement of said anti-friction means and at the same time insure a continuous pressure contact between the receptacle and its pivotal 65 mounting.

13. A receptacle unit of the class described, comprising a panel having an opening, a receptacle pivotally mounted at its lower end adjacent the rear side of said panel, a guide member extending rearwardly from said panel and adjacent the upper end of said receptacle and continuing on around a portion of said receptacle and connected to said panel adjacent the lower end of said receptacle whereby to form a reinforcing and 10 guide unit, and anti-friction means resiliently carried by said receptacle and contacting with said guide member to permit easy swinging movement of the receptacle through said opening, said resilient mounting being so arranged as to permit limited 15 bodily movement of said anti-friction means and at the same time insure a continuous pressure contact between the receptacle and its pivotal mounting and a removable container carried by said receptacle and resiliently held in position by said 20 resilient mounting.
14. A receptacle unit of the class described, comprising a panel having an opening, a receptacle pivotally mounted at its lower end adjacent the rear side of said panel, a guide member extending rearwardly from said panel and adjacent the upper end of said receptacle and continuing on around a portion of said receptacle whereby to form a reinforcing and guide unit, and anti-friction means resiliently carried by said receptacle and contacting with said guide member to permit easy swinging movement of the receptacle through said opening, said resilient mounting being so arranged as to permit limited bodily movement of said anti-friction means and at the same time insure a continuous pressure contact between the receptacle and its pivotal mounting and a removable container carried by said receptacle and resiliently held in position by said 30 resilient mounting.
15. An ash receptacle unit of the class described, comprising a panel having an opening, a pivotal mounting for the lower end of said unit, a guide member adjacent the upper part of said unit and having an arcuate guide surface, an anti-friction bearing resiliently mounted adjacent the upper rear edge of said receptacle and adapted to contact with said guide surface to permit easy movement of said receptacle about said pivot, said resilient mounting being of such strength as to per- 40
- mit easy swinging movement of said receptacle because of the anti-friction contact between the bearing and the guide surface and at the same time maintain sufficient pressure between said receptacle and the pivotal mounting to prevent rattling, and a stop member adjacent one end of said guide surface and against which said bearing rests when the receptacle is in open position, said resilient mounting permitting bodily movement of said bearing whereby to pass by said stop member when it is desired to remove the receptacle through said opening. 5
16. An ash receptacle unit of the class described, comprising a panel having an opening, a swinging receptacle the lower end of which is pivotally mounted, a guide member extending rearwardly from said panel and having an arcuate guide surface, a spring on the upper rear part of said receptacle and a roller bearing carried by said spring and contacting with said guide surface to 15 permit easy movement of said receptacle, said spring being so arranged and of sufficient strength as to hold said receptacle in said pivotal mounting under pressure at all times to prevent rattling, said guide surface being of just sufficient length 20 that the roller bearing will pass under one end thereof to resiliently hold the receptacle in open position. 25
17. An ash receptacle unit of the class described, comprising a panel having an opening, a swinging receptacle the lower end of which is pivotally mounted, a guide member extending rearwardly from said panel and having an arcuate guide surface, a spring on the upper rear part of said receptacle, and a roller bearing carried by said 30 spring and contacting with said guide surface to permit easy movement of said receptacle, said spring being so arranged and of sufficient strength as to hold said receptacle in said pivotal mounting under pressure at all times to prevent rattling, said guide surface being of just sufficient length 35 that the roller bearing will pass under one end thereof to resiliently hold the receptacle in open position, said roller bearing being bodily movable about said spring mounting to permit removal of the receptacle through the panel opening. 40

WILLIAM G. VOGEL.
